BUCKLE

Filed June 24, 1930

Inventor

Louis Alterson
By his Attorney

Harry Rodriguez

UNITED STATES PATENT OFFICE

LOUIS ALTERSON, OF NEW YORK, N. Y.

BUCKLE

Application filed June 24, 1930. Serial No. 463,396.

This invention relates to a buckle or similar fastening device and has for its object to provide an article of this character particularly intended for use upon shoes, belts, wrist 5 watches and many other articles.

The primary object of my invention is to provide a buckle which shall be extremely simple in construction and design and which shall be sturdy and extremely unlikely to 10 break during ordinary use.

A further object of the invention is to provide a type of buckle of such form that the same may be conveniently used upon shoes and similar articles by reason of its compactness and general design. Its construction and arrangement is such that it is neat and inconspicuous in appearance, it has no protruding or extended parts likely to injure the wearer when used upon a shoe or the like and in 15 addition, presents an ornamental aspect and greatly enhances the appearance of the article to which it is attached.

While I describe my improved buckle as being particularly applicable to shoes and 20 similar articles, it will be readily understood that the same can be used upon numerous articles, garments and devices wherever a buckle may properly and suitably be used as a fastening instrumentality.

With these objects and such other objects as may hereinafter appear, I have devised the particular arrangement of parts set forth below and more particularly pointed out in the 25 claim appended hereto.

Reference is to be had to the accompanying drawing, forming a part hereof in which

Figure 1 is a front elevation of a buckle made in accordance with my invention, showing the same attached to a strap, band or the 30 like;

Figure 2 is a side elevation of the buckle;

Figure 3 is a front view of the buckle showing the manner in which it appears when connecting together the straps of a shoe or 35 other article; and

Figure 4 is a sectional view on the line 4—4 of Figure 1, looking in the direction of the arrows.

In the preferred embodiment of my invention, 1 indicates the frame of the buckle. The

same is preferably of generally elongated contour and is provided at its opposite ends with similar loops 2 and 3 which are integrally connected by a pair of parallel side frame members 4 and 5. A cross bar 6 located intermediate of the loops extends between and joins the side frame members 4 and 5 and a buckle tongue 7 is freely pivoted on the cross bar, said tongue having one of its ends looped about the cross bar 6 and its free end normally resting on the face of the loop 3. 55

It will be seen that the openings 8 and 9 within the looped members 2 and 3 are of greater transverse dimension than the space between the two side frame members 4 and 5. 60 In other words, the buckle frame is of contracted dimension at its central portion and is provided with flared loops at its opposite ends for a purpose to be hereafter described. 65

At 10 is disclosed one of the straps of a shoe; one end of a belt or the like. The same is provided with a loop 11 which encompasses the cross-bar 6 and is apertured at 12 to permit the passage of the tongue 7. At 13 is shown another end of the strap which is provided with the usual hole 14 through which the tongue 7 passes. The strap 13 is extended up through the opening 8 in the loop 3 and the tongue 7 then passes through the hole 14. The end of the strap 13 is then projected 70 downwardly through the loop opening 9 and under the loop member 2 as clearly disclosed 75 in Figures 3 and 4.

It will be noted that the width of the strap 13 is sufficient to wholly overlie the contracted portions of the frame, that is, the frame side members 4 and 5, and completely conceal the same. The strap 13, extending through both loops covers and conceals the cross bar 6 and the looped strap end 11 secured thereto. 80

Thus, when the buckle is viewed from the front as in Figure 3, it presents the appearance of two independent spaced loops. In buckles of the present day construction, the longitudinal sides are so extended that the same protrude far out beyond the edges of the straps or belts to which they are applied. These protruding parts not only seriously detract from the appearance of the buckle, 85 but sometimes provide protruding edges 90

which cause discomfort to the wearer of articles on which such buckles are used.

Through the construction of my improved buckle, these protruding edges are not only concealed by the straps or bands to which they are attached, thus enhancing their appearance, but they also measurably protect the wearer from contact with these edges.

While I have described my buckle as being applied to shoe straps or similar articles, it will be understood that it may well be used as a belt buckle or in various environments where a buckle of the appearance and desirable features presented by that forming the subject of my invention may aptly be used.

While I have shown one embodiment of my invention, it is obvious that the same is not to be restricted thereto but is broad enough to cover all structures coming within the scope of the annexed claim.

What I claim is:—

A buckle for connecting two strap ends, said buckle having a frame provided with a pair of elongated side bars, the opposite ends of said bars integrally and rigidly connecting with similar fixed enlarged loops and maintaining said loops spaced at a distance apart, the space defined by the inner edge of each of said loops being greater than the distance between the outer edges of the two side bars, said loops receiving one of the strap ends, said strap end being passed through both loops and closely fitting said loops and extending over and concealing the side bars, a cross bar connecting the two side bars between the loops, said cross bar being provided with a pivoted tongue, said cross bar receiving the other strap end and being concealed from view by the first mentioned strap end that passes through the two loops on the buckle frame.

Signed at the city, county, and State of New York, this 23rd day of June, 1930.

LOUIS ALTERSON.
